UNITED STATES PATENT OFFICE

WILLIAM E. WINE, OF TOLEDO, OHIO

CROSS BEARER

Application filed April 3, 1928. Serial No. 267,040.

My invention relates to new and useful improvements in cross bearers for railway cars and has for one of its objects the provision of a cross bearer comprising a substantially unitary casting.

Another object of the invention is to provide a cross bearer of truss form from end to end.

Another object of the invention is to integrally provide the cross bearer with legs or arms adapted to be rigidly secured to adjacent side stakes intermediate the ends of the latter.

A further object of the invention consists in providing the cross bearer with means to which hopper sheets may be rigidly secured.

A primary feature of the invention consists in providing the cross bearer with upper and lower chord members and with upwardly extending diverging legs integrally formed with the upper chord member and adapted to be secured to car side stakes.

Another feature of the invention resides in providing the central portion of the cross bearer with depending members adapted to be rigidly secured to opposite sides of the car center sill.

A still further feature of the invention consists in forming the lower chord member of the cross bearer with means to which hopper sheets may be rigidly secured.

A still further feature of the invention consists in forming the cross bearer with top and bottom chord members which are connected by diagonal strut members diverging upwardly from adjacent the central portion of the lower chord.

Other and more specific features of the invention residing in advantageous forms, combinations and relations of parts will hereinafter appear and be pointed out in the claims.

In the drawings—

Figure 1 is a fragmentary transverse sectional view of a railway hopper car, and cross bearer being in elevation.

Figure 2 is an enlarged fragmentary side elevational view of the cross bearer.

Figure 3 is a plan view of the construction illustrated in Figure 2.

Figure 4 is a bottom view of the construction illustrated in Figure 2.

Figure 5 is an end view of the same construction.

Figure 6 is a sectional view taken on the line 6—6, Figure 2.

Figure 7 is a sectional view taken on line 7—7, Figure 2.

Figure 8 is a sectional view taken on line 8—8, Figure 2.

Figure 9 is a sectional view taken on line 9—9, Figure 2.

Referring more particularly to the drawings, 1 indicates the box-like center sill structure comprising beam members 32 respectively provided with upper and lower flanges 33 and 34, the former being connected by a cover plate 9. The side sills of the car, designated by the reference numeral 2, are preferably formed with oppositely projecting upper and lower substantially vertical flanges 35 and 36 respectively connected by an intermediate inclined web portion 37. The car sides may be advantageously formed by a plurality of sheets 23 respectively secured along their lower edges to the upwardly projecting flanges 35 of the adjacent side sills. At their upper edges the side sheets may be conveniently secured to side top rails 4 and the latter may, if desired, be reinforced and strengthened by suitable shaped brackets 5.

The cross bearer, generally designated by the reference numeral 6, is preferably in the form of a truss having substantially horizontally disposed top and bottom chord members 12 and 7 respectively. Each of these chord members is preferably of T-section having a top flange and a stem or depending portion, the upper surface of the flange being cambered as at 19 so as to shed portions of the lading as it is being discharged from the car through the drop doors (not shown) in the bottom thereof.

The bottom chord member 7 extends continuously from one side of the car to the other, while the top chord member 12 terminates inwardly of the car sides. Adjacent their extremities the chord members are connected by diagonally disposed strut members

11 which respectively converge upwardly from the outer ends of the lower chord. Intermediate their ends the chords are connected by a plurality of pairs of struts 13 and 14 respectively. The struts 14 diverge downwardly from the central portion of the upper chord 12 intersecting the lower chord on opposite sides of the transverse axis of the cross bearer. The struts 13 respectively diverge upwardly from adjacent the points of intersection of the struts 14 with the lower chord member to the points of intersection of the struts 11 with the upper chord.

At its central portion the lower chord member is provided with a pocket 8 adapted to receive the center sill 1, the pocket being defined by the central portion of the lower chord member, the flange of which is preferably enlarged at this point as at 15, and the spaced depending walls or flanges 28 which are provided with a plurality of apertures 29 for receiving any suitable means such as rivets for rigidly connecting them to opposite sides of the center sill. Immediately above the center sill the marginal edges of the enlarged portion 15 of the flange of the lower chord member is provided with downwardly depending portions 38 which terminate in laterally projecting flanges 30. The depending portions 38 are, as will be seen from the drawings, triangularly shaped and serve as gussets to reinforce the depending flanges 28. The flanges 30 diverge downwardly from adjacent the flange of the lower chord to afford convenient means for supporting hood sheets 10 which overlie the top cover plate of the center sill to cause the loading within the car to readily pass on opposite sides of the sill as it is being discharged.

At its opposite ends the cross bearer is preferably integrally formed with portions adapted to be rigidly secured to the side sills. These end portions project on opposite sides of the stem of the lower chord member and each is formed with a substantially vertical portion 39 for attachment to the upper flange 35 of the sill, an inclined portion 40 engageable with the web 37 of the sill and a substantially vertical portion 41 for attachment to the lower flange 36 of the sill. From the foregoing it will be perceived that the cross bearer is integrally formed with portions or flanges which may be conveniently and rigidly secured to the center sill and side sills.

The lower portion of the cross bearer may advantageously be integrally fashioned with means to which adjacent portions of the car hoppers, such as the sheets 25, may be secured. Thus, the end portions of the bearer are respectively provided with pairs of inwardly projecting flanges 24 while the depending centrally disposed flanges 28 are respectively provided with outwardly projecting pairs of flanges 27. The flanges of each of the pairs diverge downwardly from

the stem of the lower chord member so as to respectively lie in planes parallel with the planes in which the adjacent portions of the hopper sheets are disposed. Furthermore, the portions of the stem of the lower chord member between the flanges 24 and 27 on each side of the center sill are formed with a plurality of apertures 26 for receiving rivets for attaching the marginal edges of the hopper sheets thereto, the sheets, of course, terminating in substantially vertically disposed flanges so that their connection with the lower chord member may be readily effected.

The lower ends of the cross bearer may be also conveniently formed with upwardly projecting flanges or pads 21 for connection to the inside side stakes 3. Although any particular form of side stake may be employed, that chosen for purposes of illustrating the invention is of bulb angle form, one leg of which is secured to the inner faces of the side sheets and the other leg of which projects inwardly into the car for attachment to the cross bearer. Projecting from the portions or flanges 21 of the cross bearer on the sides thereof opposite to which the side stakes are secured are flanges 22, permitting direct connection between the side sheets 23 and the cross bearer.

In order to brace the sides of the car and to rigidly tie them to the cross bearer the latter is formed with upwardly projecting outwardly inclined legs or arms 17, the outer ends of which are formed with pads or flanges 18 to be rigidly secured to the adjacent side stakes at points above the top of the cross bearer. These arms or legs 17 are arranged so as to constitute, in effect, continuations or prolongations of the strut members 13. The arms or legs 17 are preferably T-shape in section and their flanges are preferably the same width as the flanges of the top and bottom chord members. All of the strut members are advantageously formed with substantially vertical flanges disposed in the same plane as the stems or depending portions of the two chord members and arms and with flanges which project in the same direction and are of substantially the same width as the flanges of the chords and arms. Thus, it will be appreciated that since all of the vertical disposed flanges of the cross bearer are disposed in the same plane they constitute continuations of each other, thereby providing the bearer with what, in effect, constitutes apertured web portions. To further rigidify the bearer the stems of the top chord member and arms and practically all of the vertically disposed flanges of the strut members may be formed with beads 20. Also, to strengthen the cross bearer at the point of intersection of the flanges of the top chord 12 and the arms or legs 17 it may be formed with triangularly shaped gussets or ribs 31. By providing the cross bearer with strut

members which extend diagonally upward from the sides of the center sill, at which points it is subjected to the greatest loads, deformation of the bearer is effectively prevented. Furthermore, the bearer is so formed that not only does it serve as a rigid transverse load carrying member but also serves to brace and tie together the car sides. Also by forming the bearer with integral means to which adjacent portions of the car hoppers may be attached a more rigid and economical car construction is produced.

I claim:

1. A cross bearer for freight cars integrally formed with upwardly extending diverging legs adapted to be respectively secured to car side stakes.

2. A cross bearer of truss formation involving legs formed integrally therewith adapted to be respectively secured to car side stakes in a plane above the top of the truss.

3. A cross bearer of truss formation having upper and lower chord members and diagonal strut members, said top chord member being integrally formed with upwardly extending diverging legs adapted to be secured to car side stakes.

4. A cross bearer having V-shaped end portions, the apices of said end portions being connected by a substantially horizontally disposed member, the extremities of said portions being adapted to be secured to car side stakes.

5. A cross bearer for freight cars having a pocket formed centrally thereof to receive a center sill inclined flanges on the opposite side walls of the pocket, inclined flanges at the outer ends of the cross bearer, and all of said flanges adapted to receive and support the upper ends of the hopper sheets.

6. A cross bearer for freight cars comprising a regular truss, legs adapted to be connected at their outer ends to the side stakes of a freight car, and inclined flanges disposed along the lower edge of the truss member for supporting and securing the upper ends of the hopper sheets.

7. A cross bearer for freight cars comprising a lower member, inclined members and top member, flanges along the lower member inclining from the said lower member at the opposite sides and said flanges adapted to secure hopper sheets.

8. A cross bearer for freight cars comprising a central pocket adapted to fit over a center sill, inclined flanges on the side walls of the pocket, inclined flanges on the outer ends of the cross bearer, and hopper sheets secured to the said flanges.

9. A cross bearer of ribbed formation for freight cars, the opposite ends of the bearer being in the shape of four diverging legs, a bottom member having a pocket formed therein and supporting flanges thereon, said legs adapted to be secured to the side stakes of a

car and the flanges adapted to be secured to the hopper sheets of a car.

10. A cross bearer for freight cars comprising a unitary structure throughout, said cross bearer arranged to be tied to the side and center sills and the side stakes of the car, and supporting flanges along the lower part of the cross bearer and extending at right angles to the axis of the bearer for supporting adjacent hopper sheets.

11. A cross bearer for a freight car comprising an integral structure provided with oppositely extending flanges to receive the upper ends of the hopper sheets, the said cross bearer provided with upwardly extending legs adapted to be secured to the side stakes of the car at points above the normal level of the cross bearer.

12. A cross bearer of ribbed formation comprising a plurality of triangles, the lower portion of the cross bearer provided with a pocket to receive a center sill, the outer ends of the cross bearer at its lower end conforming to the shape of the side sills, and means along the lower member of the cross bearer to receive the upper ends of the hopper sheets.

13. A cross bearer of integral ribbed formation, the lower portion of said bearer provided with depending members for attachment to a center sill structure, said lower portion being adapted to receive and support hopper sheets.

14. A cross bearer of integral ribbed formation, the lower portion of said bearer provided with depending members for attachment to a center sill structure, said lower portion having a flange adapted to receive and support hopper sheets, said depending members provided with flanges for assisting in the support of the said hopper sheets.

15. A cross bearer of integral ribbed formation, the lower portion of said bearer provided with depending members for attachment to center sill structure, said lower portion being adapted to receive and support hopper sheets and means located between said depending members at opposite sides of the cross bearer for supporting center sill hood sheets.

16. A cross bearer of integral ribbed formation, the lower portion of said bearer provided with depending members for attachment to a sill structure and provided with a portion adapted to support hopper sheets.

17. A cross bearer of integral ribbed formation, the lower portion of said bearer being provided with means for attachment to a sill structure, the outer ends of said bearer being provided with means adapted to support the lower ends of side stakes and the top portion of said bearer being provided with an arm at each end adapted to be connected to the side stakes intermediate the ends of said side stakes.

18. A cross bearer of ribbed formation the

- lower portion of said bearer being provided with means for attachment to a center sill structure, the outer lower ends of said bearer provided with means adapted to be secured 5 to the lower ends of respective side stakes, an arm extending upwardly from each side of the bearer adapted to be secured to its respective side stake at a point spaced below the top end of said side stake.
- 10 19. A cross bearer of integral formation, the lower portion of said bearer provided with depending members for attachment to a sill structure and further provided with portions adapted to support hopper sheets, 15 means on the opposite ends of the bearer adapted to be secured to the lower ends of oppositely positioned side stakes, arms respectively extending upwardly and outwardly from the bearer, and each adapted to be 20 secured to its respective side stake at points substantially midway between the upper and lower end of the same.
20. A cross bearer of integral ribbed formation, provided with means on its lower 25 portion for attachment to a center sill, further means on the lower portion of said cross bearer for supporting hopper sheets, the outer ends of said cross bearer adapted to be secured to and support side stakes, an upwardly extending arm on each side of the 30 bearer and each adapted to be also secured to its side stake at a point intermediate the upper and lower ends of said side stake.
21. A one-piece transverse load-carrying 35 member for car bodies having diagonal strut members with their lower ends so disposed as to lie over the sides of the center sill in an assembled car body.
22. In car construction, a center sill, and 40 a one-piece transverse load-carrying member having strut members extending diagonally upward from the sides of the sill.
23. In car construction, a center sill, and a one-piece transverse load-carrying member 45 having strut members extending diagonally upward from the sides of the sill to the top of the member.
24. In a car structure, a center sill, and a transverse load-carrying member having diagonal strut members extending from the 50 bottom bar of the member to the top bar of the same, some of said struts having their lower ends connected to the bottom bar, immediately above the sides of the center sill.
- 55 25. A cross bearer for railway hopper cars adapted to be disposed above the car center sill, said bearer being of truss formation and being integrally formed with spaced depending flanges respectively adapted to be secured 60 to opposite sides of the center sill, each of said flanges having portions for supportingly cooperating with adjacent hopper sheets.
26. A cross bearer for railway hopper cars adapted to be disposed above the car center 65 sill, said bearer being of truss formation and having end portions adapted to be respectively secured to the car side sills, each of said end portions having flanges for supportingly cooperating with adjacent hopper sheets.
- 70 27. In a railway hopper car, the combination with hopper sheets, of a cross bearer of truss formation having upper and lower chord members, said hopper sheets being secured to said lower chord member.
28. In a railway hopper car, the combination with hopper sheets, of a cross bearer having a horizontally disposed member of substantially T-shape, said hopper sheets being secured to the stem of said T-shaped member.
- 75 29. In a railway hopper car, the combination with hopper sheets, of a cross bearer having a substantially horizontally disposed member and a plurality of downwardly inclined flanges, said hopper sheets being secured to said member and flanges.
- 80 30. In a railway hopper car, the combination with a plurality of hopper sheets, of a cross bearer having a substantially horizontally disposed member and a plurality of pairs of flanges, the flanges of each pair diverging downwardly and arranged on opposite sides of said member, the hopper sheets being secured to the said member and flanges.
- 85 31. In a railway hopper car, the combination with a plurality of hopper sheets, of a cross bearer having a substantially horizontally disposed T-shaped member and a plurality of pairs of flanges, the flanges of each pair diverging downwardly from the stem of said T-shaped member, said hopper sheets being secured to said stem and flanges.
- 90 32. A cross bearer of truss formation involving top and bottom chord members, strut members converging upwardly from adjacent the outer ends of the bottom member, and legs diverging upwardly from adjacent the point of intersection of the strut members and top chord member for attachment 95 to side stakes of the car.
- 100 33. A cross bearer of truss formation involving top and bottom chord members, strut members converging upwardly from adjacent the outer ends of the bottom member, and strut members diverging upwardly from adjacent the central portion of the bottom member, said diverging and converging strut members intersecting adjacent the ends of the top chord member.
- 105 34. A cross bearer of truss formation involving top and bottom chord members, and upwardly converging strut members respectively connecting the extremities of said chord members.
- 110 35. A cross bearer of truss formation involving top and bottom chord members, strut members converging upwardly from adjacent the ends of said bottom member, strut members diverging upwardly from the cen- 115

- tral portion of the bottom member, and strut members diverging downwardly from adjacent the central portion of the top member.
36. A cross bearer of truss formation involving top and bottom chord members, strut members converging upwardly from adjacent the ends of said bottom member, and strut members diverging upwardly from adjacent the central portion of the bottom members, said converging and diverging strut members respectively intersecting adjacent the extremities of said top chord member.
37. A cross bearer of truss formation involving top and bottom chord members, strut members converging upwardly from adjacent the extremities of said bottom member, strut members diverging upwardly from adjacent the central portion of the bottom member, said converging and diverging strut members respectively intersecting adjacent the extremities of the top chord member, and strut members diverging downwardly from adjacent the central portion of the top member, said last-named strut members respectively intersecting the bottom chord member adjacent the lower ends of said upwardly diverging strut members.
38. A cross bearer of truss formation involving top and bottom chord members, diagonal strut members, and means respectively constituting continuations of said strut members adapted to be secured to car side stakes.
39. A cross bearer of truss formation involving top and bottom chord members, and diagonally extending strut members, said cross bearer having means rigidly united thereto in substantial alinement with the strut members adapted to be secured to car side stakes.
40. A cross bearer for freight cars integrally formed adjacent its lower central portion with laterally projecting flanges adapted to supportingly cooperate with center sill hood sheets.
41. A cross bearer for railway freight cars integrally formed adjacent its lower central portion with a substantially rectangularly shaped portion, one pair of the opposite faces of said portion being formed to supportingly cooperate with center sill hood sheets and the other pair of the opposite faces of said portion being adapted to be secured to the sides of the center sill.
42. A cast metal cross bearer for railway freight cars rigidly provided with upwardly diverging legs for attachment to side stakes of the car.
43. A cross bearer for railway freight cars involving top and bottom chord members, and legs rigid with said top chord member and diverging upwardly therefrom for attachment to side stakes of the car.
44. A cross bearer for railway freight cars involving top and bottom chord mem-
- bers, strut members extending upwardly from the lower chord member to adjacent the ends of the upper chord member, and legs diverging upwardly from adjacent the ends of the top chord member for attachment to side stakes of the car.
45. A cross bearer for railway freight cars involving top and bottom chord members, upwardly converging strut members connecting the extremities of the chord members, and legs diverging upwardly from adjacent the point of intersection of the top chord member and strut members for attachment to side stakes of the car.
46. A cast metal cross bearer for railway freight cars involving top and bottom chord members, said bottom chord member being of substantially T-shape and being integral- 80
ly provided with depending members adapt- 85
ed to be secured to opposite sides of the center sill of the car, said bottom chord and de- 90
pending members being connected by a plu- 95
rality of ribs extending longitudinally of the bearer.
47. A cross bearer for railway hopper cars having downwardly depending members adapted to be secured to opposite sides of the car center sill, each of said members having a laterally projecting portion for supportingly cooperating with a sheet of an adjacent hopper of the car.
48. A cross bearer for railway hopper cars having downwardly depending members adapted to be secured to opposite sides of the car center sill, each of said members being provided with a laterally projecting flange having downwardly diverging portions, one of said portions being adapted to supportingly cooperate with an inclined floor sheet of one hopper of the car and the other of said portions being adapted to supportingly cooperate with an inclined floor sheet of another hopper of the car.
49. A cross bearer for railway freight cars having end portions for attachment to the sides of the car, each of said portions having an inwardly extending part for supportingly cooperating with an inclined floor sheet of one of the hoppers of the car.
50. A cross bearer for railway freight cars having end portions for attachment to the sides of the car, each of said portions having an inwardly extending flange pro- 110
vided with downwardly diverging portions, 115
one of said diverging portions being adapted to supportingly cooperate with an inclined floor sheet of one hopper of the car and the other of said diverging portions being adapt- 120
ed to supportingly cooperate with an inclined floor sheet of another hopper of the car.
51. A cast metal cross bearer for railway cars having end portions for attachment to the sides of the car, each of said end portions being integrally formed with means 125
130

- for supportingly cooperating with an inclined floor sheet of one of the hoppers of the car.
52. A cross bearer for a railway hopper car, each end of the cross bearer being provided with laterally offset portions for attachment to the adjacent side sill of the car, and means rigid with each end of the cross bearer for supportingly cooperating with an inclined floor sheet of an adjacent hopper of the car.
53. A cross bearer for railway cars comprising top and bottom chord members, each end of the bottom chord member being integrally provided with a portion for attachment to an adjacent side sill of the car and a portion normal to said first-named portion for attachment to a side stake of the car.
54. A cross bearer for railway cars comprising top and bottom chord members, each end of the bottom chord member being integrally provided with portions adapted to be respectively secured to a side sheet and to a side sill of the car and a portion normal to said first-named portions for attachment to a side stake of the car.
55. A cross bearer for railway cars comprising top and bottom chord members, each end of the bottom chord member being provided with a depending portion adapted to be rigidly secured to a side sill of the car.
56. A cross bearer for railway cars comprising top and bottom chord members, each end of the bottom chord member being provided with a depending portion adapted to be rigidly secured to a side sill of the car, said depending portions being respectively provided with inwardly projecting flanges for supportingly cooperating with inclined floor sheets of adjacent hoppers of the car.
57. A cross bearer for railway cars comprising a body portion and upwardly extending arms, the upper ends of said arms being enlarged for attachment to side stakes of the car.
58. A cross bearer for railway cars comprising a body portion and upwardly extending arms, each of said arms being provided with a flange and an enlarged end portion for attachment to an adjacent side stake of the car.
59. A cross bearer for railway cars comprising a body portion and upwardly extending arms, said body portion involving top and bottom chord members, the ends of said bottom chord members and arms being provided with portions adapted to be rigidly secured to side stakes of the car.
60. In a railway car, the combination with a center sill, of side sills each of which is provided with an inclined web and with flanges projecting in opposite directions from the latter, of a transverse underframe member secured to the center sill and having end portions adjacent the side sills, each of said
- end portions being rigidly secured to the oppositely projecting flanges of the side sill adjacent thereto.
61. In a railway car, the combination with a center sill, of side sills respectively having inclined webs and oppositely projecting substantially vertical flanges, an underframe member secured to the center sill and having end portions respectively conforming to the cross sectional shape of the side sills, each of said end portions being rigidly secured to the vertical flanges of the adjacent side sill.
62. In a railway car, the combination with a center sill, of side sills each of which is provided with an inclined portion and a substantially vertical flange, a transverse underframe member secured to the center sill and having end portions respectively adjacent the side sills, each of said end portions having an inclined portion contiguous to the inclined portion of the adjacent side sill and having a vertical portion secured to the vertical flange of the latter.
- In testimony whereof I affix my signature.
- WILLIAM E. WINE.
